UNITED STATES PATENT OFFICE

LOUIS HASBROUCK, OF SPRINGFIELD, MASSACHUSETTS

SMOKER'S APPARATUS

Application filed July 10, 1930. Serial No. 466,948.

This invention relates to improvements in smokers' apparatus and is directed more particularly to combined cigarette receptacles and lighters which co-operate with one another to form a unitary structure of novel form.

According to one object of the invention a tubular receptacle for cigarettes is provided which is made of pliable material so as to have relatively movable walls whereby it may receive and accommodate various numbers of cigarettes. The receptacle so made of pliable material is light in weight and in order to maintain its generally rectangular shape according to another object of the invention one end thereof is rigid. This is accomplished by providing a lighter which has a wick chamber the walls of which are inserted within and act as a support for the walls of the receptacle. In this way a relatively non-rigid receptacle has one rigid end whereby it holds its general shape while forwardly of said end it is free to flex or collapse and expand and in that way accommodate itself to various numbers of cigarettes which it may contain.

Various novel features and advantages of the invention will be hereinafter referred to in connection with the detail description thereof which relates to the accompanying drawing, wherein

Fig. 1 is a side elevational view of a device embodying the novel features of the invention.

Fig. 2 is an end elevational view of the same.

Fig. 3 is a sectional view on the line 3—3 of Fig. 1, and

Fig. 4 is an end elevational view of the device with the lighter mechanism omitted, and showing a flexible receptacle as it appears when expanded or filled with cigarettes.

Referring now to the drawing, the invention will be described in detail.

As one important feature of the invention a receptacle 2 is provided which is formed as a rectangular tube and has front and rear side walls 4 and 6 as well as end walls 8. These walls are arranged to provide a tubular receptacle or container of such a shape

and size that an ordinary package of cigarettes may be readily inserted therein. With the end of such a package removed the ends of the cigarettes will be accessible at the open lower end or mouth 10 of the receptacle. The receptacle will preferably be made of some suitable pliable or flexible material such as leather or the like so that its walls are yieldable whereby it may conform to the shape of a package of cigarettes. By being pliable, as cigarettes are withdrawn from the receptacle the walls thereof may collapse so as to accommodate themselves to the cigarettes remaining in the receptacle.

In Fig. 2, the receptacle is shown in collapsed condition as when it is empty. In Fig. 4, it is shown in expanded or extended condition as if it was filled with cigarettes. Folding lines 12 in the end walls 8 may be provided so as to facilitate the ready bending or flexing of these walls whereby the walls may assume either the collapsed position shown in Fig. 2 or the extended position shown in Fig. 4.

A closure flap 14 hinged to one of the walls, preferably the rear wall 6, is arranged to overlie the lower open end of the receptacle as shown in Fig. 4, so as to protect the ends of the cigarettes in the receptacle. An extension 16 at the outer end of this flap 14 is arranged to be slipped beneath a keeper strap 18 which extends across the wall 4. This keeper functions to hold the extension and thereby the closure flap across the mouth of the receptacle.

As has been stated, the walls of the receptacle are adapted and arranged to bend and flex more or less so as to be relatively movable between the collapsed position in Fig. 2 and the expanded position shown in Fig. 4. In this way as cigarettes are withdrawn from the completely filled receptacle the walls may yield more or less and close against the cigarettes remaining. In this way the size of the receptacle is variable so that with very few cigarettes in the receptacle it is of course much less in thickness than when filled.

In order that the yieldable receptacle may be held in a generally rectangular shape so as to protect the cigarettes at all times it is

provided with a rigid end opposite the open mouth thereof. According to a novel feature of the invention this rigid end is formed by front and rear walls 20 and 22 and end walls 24 of a chamber of a lighter device indicated generally at 3. The walls 20, 22, 24 and lower and upper walls 26 and 28 form a fuel chamber or well for the lighter device. The walls are preferably of metal so as to form a rigid structure and they are inserted between the corresponding walls of the receptacle and co-operate therewith to hold the end of the receptacle in shape. The walls of the receptacle are secured by adhesive material or the like to the contiguous walls of the lighter chamber.

A wick tube 30 in the upper wall 28 of the lighter chamber is hollow and carries a wick 31 which extends downwardly into the chamber. A hinged member 32 pivoted at 34 to a stud 36 on the wall 28 is arranged for swinging movements from the position shown in Fig. 1 to a position where it rests on or overlies the wick for snuffing a flame and to prevent evaporation of fuel as well. A tube 38 mounted above the upper wall 28 carries as usual a rod of spark-emitting material 40, while a rotatable knurled wheel 42 is provided which when rotated acts on the spark material so that the wick may be ignited. A filler opening 42 in the wall 28 of the chamber is provided with a screw cap 44 so that the fuel may be poured into the chamber for saturating the wick and any other absorbent material carried therein.

The parts forming the lighter are conveniently arranged so that by grasping the receptacle in the hand the lighter may be operated as usual by the thumb or finger. As one special feature of the invention the receptacle is of such shape that it may be conveniently grasped in the hand to facilitate manipulation of the lighter. The lighter is relatively flat as distinguished from ordinary lighters and without the receptacle would not be convenient to use. It is flat as will be seen so that the combined lighter and receptacle are not bulky. For the purpose of manipulating the lighter the receptacle functions as a handle or grip.

As will be noted the walls of the receptacle

are yieldable or pliable so that they readily accommodate a full package of cigarettes and collapse as cigarettes are withdrawn. The receptacle is convenient to carry because its size depends only upon the number of cigarettes which it holds. As distinguished from a receptacle having rigid metal walls and which is not collapsible and has a definite overall size, this receptacle is less bulky and lighter in weight.

As a special feature it will be noted that the walls of the lighter chamber provide a rigid end for the receptacle. In this way the general rectangular shape of the receptacle is maintained for protection of any number of cigarettes contained therein, while forwardly of the rigid end it is free to flex or bend to accommodate various conditions.

Having described the invention in the form at present preferred, what I desire to claim and secure by Letters Patent of the United States is:

As a new article of manufacture, the combination of a co-operating cigarette case and lighter to form a unitary structure, the said lighter including rigid upper, lower, front, rear and side walls to form a reservoir and lighting mechanism carried by said upper wall, the said case including front, rear and side walls of non-rigid light-weight material and having open ends, the said walls of the lighter being inserted at one of the open ends within the said walls of the case and secured thereto whereby the said end of the non-rigid case is made relatively rigid by the walls of the lighter and whereby the rigid lower wall of the lighter serves as an end wall of the case and provides a protection for cigarettes in said case, the side walls of said case being bendable along longitudinal lines whereby the front and rear walls may be moved between a position parallel with said side walls of said lighter and a position where the walls converge therefrom, a closure flap of flexible material carried by the end of the rear wall of the case opposite the said rigid end and means on the front wall of said case for engaging said flap.

In testimony whereof I affix my signature.

LOUIS HASBROUCK.
